UNITED STATES PATENT OFFICE

LEO NEJELSKI, OF UNIVERSITY CITY, MISSOURI, ASSIGNOR OF ONE-HALF TO FRANK X. TRIMBACH, OF UNIVERSITY CITY, MISSOURI

DESIGN FOR A JAR OR SIMILAR RECEPTACLE

Application filed August 13, 1930. Serial No. 36,662. Term of patent 14 years.

To all whom it may concern:

Be it known that I, LEO NEJELSKI, a citizen of the United States, residing in University City, St. Louis County, State of Missouri, have invented a new, original, and ornamental Design for a Jar or Similar Receptacle, of which the following is a specification, reference being had to the accompanying drawings, forming part thereof, in which—

Fig. 1 is a top plan view, showing my new design.

Fig. 2 is a side elevation, showing my new design.

The design comprises a substantially globular device having a snow white surface having irregular rises and intervening grooves and spaces, and having numerous deep depressions in and around its upper portion.

I claim:

The ornamental design for a jar or similar receptacle substantially as shown and described.

LEO NEJELSKI.
